UNITED STATES PATENT OFFICE.

ALFRED E. HOERMANN, OF NEW YORK, N. Y.

HAT-FRAME MACHINE.

No. 894,648.

Specification of Letters Patent. Patented July 28, 1908.

Application filed October 24, 1907. Serial No. 398,960.

To all whom it may concern:

Be it known that I, ALFRED E. HOERMANN, a citizen of the United States, residing at 123 West One hundred and twenty-seventh street, in the borough of Manhattan, in the city, county, and State of New York, have invented certain new and useful Improvements in Hat-Frame Machines, of which the following is a specification.

10 This invention relates to certain improvements in that class of machines which are particularly designed and adapted for use in the manufacture of the frames of ladies' hats, and the object of the invention is to provide 15 a machine of this general character of a simple and comparatively inexpensive nature, and of a compact, strong and durable construction having certain features of novelty pertaining to the hat wire guiding or supporting devices whereby the improved machine 20 is made capable of more convenient and accurate adjustment and a material economy of time, together with improved operation of the machine as regards the uniformity of the 25 work accomplished thereon are attained without requiring any particular skill on the part of the operator.

The invention consists in certain novel features of the construction, and combinations and arrangements of the several parts 30 of the improved hat frame machine, whereby certain important advantages are attained and the device is rendered simpler, cheaper and otherwise better adapted and more convenient for use, all as will be hereinafter fully set forth.

The novel features of the invention will be carefully defined in the claims.

In the accompanying drawings which 40 serve to illustrate the invention Figure 1 is a side elevation showing a hat frame machine constructed according to the invention with a number of the wire guiding or supporting devices removed therefrom; Fig. 2 is a plan view of the machine as shown in Fig. 1; Fig. 3 is a side elevation showing one of the wire guiding or supporting devices removed from the machine; Fig. 4 is a side view similar to Fig. 3, but taken at the opposite side of the 45 wire guiding or supporting devices; Fig. 5 is an enlarged sectional view taken vertically through the wire guiding or supporting devices and also through the lateral supporting arm of the machine whereon said devices are 50 secured and showing certain features of construction which will be hereinafter de-

scribed, and Fig. 6 is an enlarged plan view of the wire supporting or guiding devices as shown in Figs. 1 and 2, together with the means for holding said devices upon the lateral arm of the machine. 60

As shown in these views, the machine comprises a base 1 whereon is held for turning or rotative movement a pedestal 2, the upper end of which carries a circular table or 65 head divided into two sections 3 and 4, the section 3 being secured to the pedestal 2, while the opposite section 4 is hinged as seen at 5 upon the section 3, so as to be adapted to be raised and lowered in a well 70 known way for disengaging the wire guiding or supporting devices from the hat frame after the latter shall have been completed.

Upon the circular head or table formed of the hinge-connected sections 3 and 4 are produced radially extended arms 6; 6, herein shown as eight in number. The arms 6, 6, are evenly spaced around the head or table and are integrally formed with the respective sections 3 and 4 from which such arms are 80 extended. There is no particular novelty in the construction above described, and for that reason such construction is not claimed herein, nor is the present invention in any way limited to use in connection with such 85 construction.

The arms 6, 6 are provided with longitudinal slotted openings 7, 7, one of which is herein shown upon each such arm, and each of such slotted openings 7 is adapted for the 90 passage of two bolts 8, 8 each having at one end a head or enlargement 9, while its opposite end is made screw-threaded to receive a nut 10.

11 represents a carrying member formed 95 from flat or plate metal, and provided at its lower edge with spaced notches 12, 12, which are adapted to be slipped down over the shanks of the bolts 8, 8, of one of the arms 6, so that said plate or member 11 may be fitted 100 flush against the side of such arm 6, in position to be clamped and securely held thereon by the pressure of the heads 9, 9, of said bolts 8, 8, when the nuts 10, 10, of the said bolts shall have been tightened to effect this 105 result. In the accompanying drawings only one of the arms 6 of the machine is shown provided with the member or plate 11, but it will be understood that in the operation of the machine such a plate or member 11 will 110 be clamped upon each of said arms 6. The notches 12, 12 of each plate 11 are reversely

inclined so that as the plate is slipped over the bolts 8, 8, the inclination of said notches will serve to press the said bolts in opposite directions and in secure contact with the ends 5 of the slotted opening 7.

The plate or member 11 has an upper edge portion which is adapted, when the member is secured upon the arm 6, to extend above said arm, as clearly shown on the drawings at 10 14, and such upwardly extended portion 14 is provided with a horizontally extended slotted opening 15, alined with the length of said arm 6, and adapted for the passage of one or more bolts 17, there being two such 15 bolts herein shown as passed through said slotted opening. Said bolts 17 have heads 16 bearing upon one side of the plate or member 11, their opposite ends being screw-threaded to receive nuts 19.

20 18 and 20, represent washers held upon the bolts 17, and 21, 21, represent the slotted body portions of the hat wire guides or supports, each of which is provided with a hook-like upper extremity adapted for engagement with the hat-wire in the forming of the hat frames upon the machine, in a well known way. The said slotted body portions 21, 21 of the wire guides or supports are adapted to be adjustably held upon the bolts 17, which 25 are passed through their slots, and the washers 18 and 20 are adapted to bear upon opposite faces of said body portions, as shown in Figs. 5 and 6, the washers 18 serving to permit tightening of the nuts 19 without variation of the adjustment of said wire guides or supports, while the washers 20 act as spacers to permit the lower ends of said wire 30 guides or supports to clear the heads 9 of the clamping screws 8.

40 In the operation of the machine, the carrying members or plates 11 being clamped upon the arms of the machine, one or more of the hat wire guides or supports will be adjusted upon each of the bolts 17, according to the 45 particular style of hat frame which it is desired to make upon the machine, and after being adjusted, said guides or supports will be clamped by the tightening of the nuts 19 so as to be securely held in place during the 50 manufacture of the hat frames. The slotted openings 15 in the plates or members 11 permit the screws 17 to be adjusted toward or from each other, and while there are two such screws herein shown passed through 55 said opening, it is evident that but one such screw or any desired number thereof may be employed according to the circumstances.

After the hat wire supports or guides shall have been once adjusted upon the plates or 60 members 11, and after the work in hand at the time shall have been completed, the plates or members 11 are to be detached from the arms 6 of the machine, carrying with them the wire supports or guides without change of adjustment, and these parts so

removed are to be laid aside until such time as other hat frames of the style to which such parts are adjusted are to be made upon the machine, whereupon such parts may again be used. In this way it will be seen that a plurality of sets of the plates or members 11 and of the wire guides or supports carried thereon may be provided, and each set may be adjusted for making a special style of hat frame so that by simply detaching the parts of one of such sets from the machine and replacing them with another set, the machine may be adapted for making any style of hat frame which may be desired without requiring loss of time such as occurs where the wire supports or guides are separately adjusted for each particular lot of hats to be made.

This construction of the machine with detachable carrying members for the hat wire guides or supports affords a material economy in the manufacture by reason of dispensing with frequent adjustment of the parts, and dispenses with the necessity of any particular skill or care on the part of the operator in changing the machine from one style of hat frame to another, and also insures greater uniformity in the output of the machine than is possible where separate adjustment of the parts is required for each lot of hat frames made.

95 From the above description it will be evident that the improved hat frame machine is of an extremely simple and comparatively inexpensive nature and is particularly well adapted for use by reason of the economy 100 and uniformity of output attained thereby, and it will also be obvious from the above description that the device is susceptible of some modification without material departure from the principles and spirit of the invention and for this reason I do not desire to 105 limit myself to the precise form and arrangement of the several parts of the device herein set forth in carrying out the invention in practice.

110 Having thus described my invention, what I claim and desire to secure by Letters Patent is

1. A hat frame machine comprising a frame having radially extended arms, spaced 115 fastening devices carried by each such arm, supporting members each extended alongside one of said arms and having its opposite ends detachably held thereto by said fastening devices, and wire guides adjustably held upon the supporting members.

2. A hat frame machine comprising a frame having radially extended arms connected in a plurality of groups, the arms of each group being movable in unison relatively to those of another group, spaced fastening devices carried by each such arm, supporting members provided with longitudinally extended slotted openings, each supporting member being extended alongside 130

one of the radially extended arms and having its opposite ends detachably held thereto by the spaced fastening devices, wire guides, and bolts adjustably held in the slots of the respective supporting members and each adapted to hold a plurality of wire guides adjustably in relation to the corresponding supporting member.

3. A hat frame machine comprising a frame having slotted portions, fastening devices comprising bolts arranged at opposite ends of the slot of each slotted frame portion, and nuts having threaded engagement with the bolts, supporting members each extended alongside one of the slotted frame portions and having reversely inclined notches adapt-

ed for engagement with the bolts at opposite ends of the slot of the corresponding slotted frame portion, the reverse inclinations of the notches of each supporting member being adapted to force the bolts engaged therewith toward opposite ends of the slot wherein said bolts are arranged, and wire guides adjustably held upon the supporting members.

In witness whereof I have hereunto signed my name this 30th day of August 1907, in the presence of two subscribing witnesses.

ALFRED E. HOERMANN.
